OIL BURNER

Edwin T. Brace, Warrenton, Mo., assignor to
Binkley Manufacturing Company, Warrenton,
Mo., a corporation of Missouri

Application June 6, 1938, Serial No. 211,977

5 Claims. (Cl. 158—96)

This invention relates generally to oil burners and more specifically to an improved oil burner adapted for installation in a Dutch oven of the type ordinarily associated with tobacco curing barns, the predominant object of the invention being to provide a simple and efficiently operating oil burner which is capable of being installed in a Dutch oven of a tobacco curing barn without the necessity of altering the construction of the 10 Dutch oven, and whose installation in and removal from the Dutch oven may be accomplished in a simple and expeditious manner.

In preparing tobacco for the market the ripe leaves are pulled off of the tobacco plant when the plant is at full growth and starts to ripen, and the ripe leaves are strung on sticks which are transported to a curing barn wherein the sticks with the leaves hanging therefrom are arranged so that they are supported by tier poles within the curing barn. When a tobacco curing barn is ready for a curing operation to begin it is filled with hanging tobacco leaves, only enough open space being left at the lower level to permit an attendant to rush into the barn and 25 read the thermometer before incoming cool air can change its reading. Tobacco barns of the type to which the present invention relates are provided with the flues which comprise heat conduits that are arranged in a more or less tortuous manner in the lower portions of the barns, and heat produced in Dutch ovens associated with, but outside of the barns, is conducted through the conduits to cause the air within the barns to be heated and rise through the tobacco hanging 30 above the conduits.

The fuel used in the Dutch ovens of tobacco curing barns of the flue type has for many decades been wood, and the realization in recent years of the limitations of this system has caused a wide spread desire in the tobacco industry for a system which would be more efficient. One limitation in connection with the use of wood fires in curing tobacco is the difficulty of maintaining uniform heat within the barns. Because 45 of this short-coming of the wood flue tobacco curing system, much tobacco which should cure out as good grade tobacco is either lost altogether or has to be put with the cheaper grades. Another limitation of the wood flue system is 50 that the wood fires require constant attention, day and night, from the time the fires are kindled until the tobacco is completely cured. Still another limitation of this system is the growing scarcity of wood fuel in certain sections of the 55 tobacco raising country.

In view of the above and other limitations of the wood fire system of curing tobacco I have devised the simple and efficiently operating oil burner disclosed herein. One important feature of the invention is that the burners may be installed in a simple and expeditious manner in Dutch ovens of the type associated with tobacco curing barns for many years without altering the Dutch ovens.

The importance of this arrangement arises 10 from the fact that because the Dutch oven is not altered for the reception of the oil burner, and because the oil burner may be removed from the Dutch oven in a few minutes time, a break down of the oil burner would not result in the 15 loss of the tobacco in the barn, as the burner may be quickly removed and a wood fire kindled in the Dutch oven to maintain the proper heat within the barn. Also because the oil burners are located in the Dutch ovens outside of the curing 20 barns just as the wood fires were, no fumes or products of combustion get into the barns to taint the tobacco as was the case when attempts were made to employ kerosene burners within the barns for supplying the heat required for 25 tobacco curing. Additionally the use of an efficiently operating oil burner, such as the one disclosed herein, for providing the heat for tobacco curing operations entirely eliminates the limitations of the wood fire method mentioned above. 30 In other words a uniform heat may be maintained within the tobacco curing barn at all times, close attention to the heat producing medium at all times is not required, and the problem incident to obtaining wood fuel is solved by 35 the use of oil as the heat-producing fuel.

Fig. 1 is a fragmentary perspective of a tobacco curing barn and illustrating the improved oil burner associated with a Dutch oven thereof.

Fig. 2 is a horizontal section taken through a 40 tobacco curing barn showing the general arrangement of the flues and illustrating oil burners of the improved construction disclosed herein associated with the Dutch ovens of the barn.

Fig. 3 is an isometric view looking toward the 45 front of the improved oil burner.

Fig. 4 is an enlarged fragmentary vertical section taken through a Dutch oven and showing the improved oil burner associated therewith.

Fig. 5 is a fragmentary horizontal section taken 50 on line 5—5 of Fig. 4.

In the drawings, wherein is shown for the purpose of illustration, merely, one embodiment of the invention A designates in Figs. 1 and 2 a tobacco curing barn of the type to which this in- 55

vention relates. The tobacco curing barn A is provided with a pair of Dutch ovens B located outside of the barn, and disposed in communication with each of said Dutch ovens is a heat chamber C to which is connected a heat-conducting flue D through which air heated in the associated Dutch oven passes. Each flue D is arranged in a more or less tortuous form in the lower level of the barn, being extended rearwardly of the barn from the associated heat chamber, then transversely of the rear wall of the barn, then forwardly of the barn to a point adjacent to the front wall thereof, and then transversely of said front wall of the barn. From the front transverse portion of each flue a portion of said flue passes through the front wall of the barn and then extends upwardly as indicated at D' to a point above the roof of the barn where the heated air passing through the flue is discharged to atmosphere. The Dutch ovens B are built of suitable material, such as brick and each thereof is provided with an opening at its front.

The improved oil burner E disclosed herein is generally of L-shaped formation as shown to the best advantage in Fig. 4; that is to say, said oil burner includes a horizontal portion 1 which is disposed within the associated Dutch oven B, and a vertical portion 2 which is arranged in front of and closes the front opening of the Dutch oven. The oil burner E includes a base plate 3 to the front portion of which a narrow, transversely extended plate 4 is fixed. At its rear end the base plate 3 is provided with an upwardly extended flange 3' as shown in Fig. 4.

The horizontal portion 1 of the burner includes a rectangular structure made up of opposed side walls 5 and a top wall 6 and said side walls and top wall are provided with flanges 7 which are bent into contact with a vertically disposed plate 8 which forms a part of the vertical portion 2 of the burner. The flanges 7 of the side walls 5 and the top wall 6 referred to are secured by suitable securing elements 9 to said vertical plate 8, and at its upper end the vertical plate 8 is provided with an outwardly and downwardly inclined extension 10.

Supported by and partially within the rear portion of the horizontal portion 1 of the burner is a combustion chamber 11 which is formed from suitable refractory material, said combustion chamber having a top wall 12, opposed side walls 13 and a bottom wall 14 which is located at the rear of the combustion chamber. The combustion chamber 11 is provided with a forward opening 15 of substantial dimensions located between the top wall 12 and the base plate 3, and between the opposed side walls of the combustion chamber, and communicating with this opening is a rear passageway 16, forming an arch, which is formed between the inclined lower face 12' of the top wall of the combustion chamber and the top face of the bottom wall 14, and between the opposed side walls of the combustion chamber. The opposed side walls 5 of the horizontal portion 2 of the burner are provided with inclined edges 5' which extend rearwardly and downwardly from a point approximately midway of the length of said horizontal portion at the top thereof to the location of the flange 3' of the base plate 3, and the rear portions of said side walls 5 are connected to an inverted U-shaped member 17 which embraces said flange 3' of said base plate 3.

Disposed in the opening 15 of the combustion chamber 11, and suitably secured in place there-

in, is an oil pan 18 which in longitudinal section is shaped as shown in Fig. 4; that is to say the oil pan 18 includes a relatively deep portion 18a to which a forward inclined wall 18b and a rear inclined wall 18c lead. The oil pan 18 is provided also with opposed side walls 18d as shown in Fig. 3. Leading to the oil pan 18 from a tank 19, or other source of oil supply is an oil supply pipe 20, said oil supply pipe having associated therewith a regulating valve structure 21 which is fixed to the vertical plate 8, and having a gap 22 formed therein so that the attendant may see the oil as it falls through the gap from the portion of the supply pipe above the gap to the funnel 23 below the gap. The oil pan 18 is provided also with an oil overflow pipe 24 which leads from a forward extension 25 of the oil pan (Fig. 3) so that any excess oil which may be fed to the burner and not consumed in combustion may be conducted away from the burner to a safe distance from the flames thereof.

Supported with the relatively deep portion 18a of the oil pan is a plurality of absorbent wafers 26 which are formed preferably of refractory fire brick material. This material absorbs oil by capillary attraction and combustion takes place at the rear surfaces of the wafers. The wafers 26 are spaced from each other by a set of conductor bars 27 which provide small air gaps between adjacent wafers, said conductor bars extending from the front wall of the relatively deep portion 18a of the oil pan 18 rearwardly of the oil pan and upwardly at points beyond the rear edges of the wafer as shown to the best advantage in Fig. 4. Associated with the bottom wall 14 of the combustion chamber 11 is a plate 28 which in vertical section is shaped as shown in Fig. 4; that is to say the lower portion 28a is interposed between the lower face of said bottom wall 14 and the base plate 3, and a forward vertical portion 28b extends parallel with respect to the forward face of the bottom wall 14 of the combustion chamber in spaced relation with respect thereto to provide a space 29. Also the lower portion of the plate 28 is provided with an upstanding flange 28c at its rear end which contacts with a portion of the rear face of the bottom wall 14 of the combustion chamber 11, and the forward vertical portion 28b of said plate 28 is provided with a rearwardly extended horizontal portion 28d at its upper end which overhangs the top face of the bottom wall of the combustion chamber in spaced relation with respect thereto. The forward vertical portion 28b of the plate 28 is provided with a plurality of openings 30 one of which is shown in Fig. 4.

Secured to the forward face of the vertical plate 8 of the burner, and extended outwardly therefrom, is a pair of spaced apart sheet metal members 31 which in horizontal section are approximately U-shaped, said members being rendered sufficiently rigid through the use of braces 32 which are secured to said vertical plate 8 and to the forward portions of said members. The lower ends of the members 31 are spaced upwardly from the base plate 3 and the upper ends of said members are spaced downwardly from the outwardly and downwardly extended portion 10 of the vertical plate 8. The left-hand member 31 illustrated in Fig. 3 has hingedly secured thereto a cover plate 33 which is adapted to close the front portion of the burner as shown in Fig. 4, said cover plate being provided with a sight opening 34 through which an attendant may view passage of oil across the gap 22 in the oil supply

5 pipe 20, and sight openings 35 through which the attendant may view operation of the burner. Additionally the vertical plate 8 is provided with a sight opening 36 which coincides with the sight opening 34.

10 In order to secure the burner in place with respect to a Dutch oven, a pair of vertical pins 37 is employed, said pins being extended through apertures formed through the upper portion 10 of the vertical plate 8 and through the plate 4 as shown in Fig. 3. The burner is secured in place in association with a Dutch oven by driving the pins 37 into the ground. Also the pins 37 are aided in holding the burner in place by tie 15 wires 38 (Fig. 1) which are attached to the upper portions of the pins and to fastening elements 39 associated with the front wall of the tobacco curing barn A.

20 In the operation of the improved burner oil is fed from the oil container 19 through the oil supply pipe 20 to the oil pan 18 of the burner. As already stated herein the refractory fire brick material of which the wafers 26 are formed absorbs the oil by capillary attraction and combustion 25 takes place at the surfaces of the wafers. The wafers are spaced apart from each other by the conductor bars 27 and the action of these conductor bars is such that the flame impinging on the vertical faces of said conductor bars causes 30 heat to be conducted to the oil in the oil pan whereby the oil is rapidly vaporized. A part of the vapor thus generated, mixes with the primary air that flows through the narrow gaps between the wafers and is partly burned above the oil pan. Secondary air enters the burner in the lower portion thereof, moving beneath the oil pan 18, and said secondary air passes upwardly through the space 40 between the rear portion of the oil pan and the forward vertical portion 28b of the plate 28. This secondary air, so directed, is applied substantially at a right angle to the direction of flow of the primary air and oil vapor moving rearwardly of the burner and results in creation of sufficient turbulence to mix the secondary air and oil vapor thoroughly and promote 45 complete combustion. From the point where turbulence is created by the vertically moving body of secondary air the products of combustion are led through the refractory arch which is maintained at a glowing heat and thereby helps to burn off soot that might be generated by incomplete combustion. Some of the secondary air passes through the openings 38 in the forward portion 28b of the plate 28 and moves through 50 the space 29 and along the top face of the bottom wall 14 of the combustion chamber 11.

55 From the foregoing it is plain that a simple and efficiently operating oil burner is provided which may be quickly installed in or removed from a Dutch oven of a tobacco curing barn, as all that need be done to install the burner is to insert it in place, drive the pins 37 into the ground and attach the tie wires 38. The burner may be removed from a Dutch oven with equal facility by merely detaching the tie wires 38 and withdrawing the pins 37.

I claim:

1. An oil burner including an oil pan to which oil is fed from a source of supply, a plurality of upstanding elements supported by said pan and formed of material characterized by the ability to absorb oil by capillary attraction, a plurality of heat conducting members disposed between adjacent elements and of less height than said 70 elements to provide air gaps between the ele-

ments through which primary air passes, portions of said conducting members being located in said oil pan and in the path of the flames of the burner whereby heat is conducted by said conducting members to the oil in the oil pan so as to vaporize said oil, and a passageway 5 for secondary air which directs said secondary air at an angle to the direction of flow of the primary air and the vaporized oil carried thereby so as to create turbulence which thoroughly commingles the secondary air and the oil vapors.

2. An oil burner including an oil pan to which oil is fed from a source of supply, a plurality of upstanding elements supported by said pan and formed of material characterized by the ability 15 to absorb oil by capillary attraction, a plurality of heat conducting members disposed between adjacent elements and of less height than said elements to provide air gaps between the elements through which primary air passes, portions of said conducting members being located in said oil pan and in the path of the flames of the burner whereby heat is conducted by said conducting members to the oil in the oil pan so as to vaporize said oil, and a passageway 20 for secondary air which directs said secondary air at an angle to the direction of flow of the primary air and the vaporized oil carried thereby so as to create turbulence which thoroughly commingles the secondary air and the oil vapors.

25 3. An oil burner adapted for use with a Dutch oven having an opening, comprising a portion which is adapted to be disposed at the opening of the Dutch oven so as to close said opening, and a portion which is adapted to extend into the Dutch oven, a combustion chamber supported by and forming a unitary part of the burner portion which is adapted for disposition within the Dutch oven, and oil burning means 30 within said combustion chamber, said oil burning means comprising an oil pan to which oil is fed from a source of oil supply, a plurality of upstanding elements supported by said pan and formed of material characterized by the ability 35 to absorb oil by capillary attraction, a plurality of heat conducting members disposed between adjacent elements and of less height than said elements to provide air gaps between the elements through which primary air passes, portions of said conducting members being located in said oil pan and in the path of the flames of the burner whereby heat is conducted by said conducting members to the oil in the oil pan so as to vaporize said oil, and a passageway for 40 secondary air which directs said secondary air at an angle to the direction of flow of the primary air and the vaporized oil carried thereby so as to create turbulence which thoroughly commingles the secondary air and the oil vapors.

4. An oil burner adapted for use with a Dutch oven having an opening, comprising a portion which is adapted to be disposed at the opening of the Dutch oven so as to close said opening, and a portion which is adapted to extend into the Dutch oven, a structure formed of refractory material supported by and forming a unitary part of the burner portion which is adapted for disposition within the Dutch oven, said refractory structure providing a combustion chamber and an arch, and oil burning means disposed within the combustion chamber provided by said refractory structure, said oil burning means comprising an oil pan to which oil is fed from a source of oil supply, a plurality of up- 55

standing elements supported by said pan and formed of material characterized by the ability to absorb oil by capillary attraction, a plurality of heat conducting members disposed between adjacent elements and of less height than said elements to provide air gaps between the elements through which primary air passes, portions of said conducting members being located in said oil pan and in the path of the flames of the burner whereby heat is conducted by said conducting members to the oil in the oil pan so as to vaporize said oil, and a passageway for secondary air which directs said secondary air at an angle to the direction of flow of the primary air and the vaporized oil carried thereby so as to create turbulence which thoroughly commingles the secondary air and the oil vapors.

5. An oil burner adapted for use with a Dutch oven having an opening, comprising a portion which is adapted to be disposed at the opening of the Dutch oven so as to close said opening, and a portion which is adapted to extend into the Dutch oven, a structure formed of refractory material supported by and forming a unitary part 10 of the burner portion which is adapted for disposition within the Dutch oven, said refractory structure providing a combustion chamber and

an arch, and oil burning means disposed within the combustion chamber provided by said refractory structure, said oil burning means comprising an oil pan to which oil is fed from a source of oil supply, a plurality of upstanding elements supported by said pan and formed of material characterized by the ability to absorb oil by capillary attraction, a plurality of heat conducting members disposed between adjacent elements and of less height than said elements 15 to provide air gaps between the elements through which primary air passes, portions of said conducting members being located in said oil pan and in the path of the flames of the burner whereby heat is conducted by said conducting members to the oil in the oil pan so as to vaporize said oil, a main passageway for secondary air which directs said secondary air at an angle to the direction of flow of the primary air and the vaporized oil carried thereby so as to create turbulence which thoroughly commingles the secondary air and the oil vapors, and an apertured plate spaced from a portion of said refractory structure to provide an auxiliary passageway 20 for secondary air between said plate and said portion of said refractory structure.

EDWIN T. BRACE.
